UNITED STATES PATENT OFFICE.

WILLIAM C. MEYER, OF BEVERLY, MASSACHUSETTS, ASSIGNOR TO UNITED SHOE MACHINERY COMPANY, OF PATERSON, NEW JERSEY, A CORPORATION OF NEW JERSEY.

SHOE-SEWING MACHINE,

1,177,581.

Specification of Letters Patent.

Patented Mar. 28, 1916.

Application filed July 29, 1913. Serial No. 781,785.

To all whom it may concern:

Be it known that I, WILLIAM C. MEYER, a citizen of the United States, residing at Beverly, in the county of Essex and State of Massachusetts, have invented certain new and useful Improvements in Shoe-Sewing Machines; and I do hereby declare the following to be a full, clear, and exact description of the invention, such as will enable 10 others skilled in the art to which it appertains to make and use the same.

This invention relates to shoe sewing machines, and more particularly to sole sewing machines provided, with a straight hook 15 needle and devices cooperating therewith to form a chain stitch in which the work is supported by a rotatable work support or horn which extends within the shoe, such machines being generally known in the art 20 as machines of the McKay type.

In general, the object of the invention is to produce a simple and compact machine of the McKay type, which will run smoothly at high speed, which will produce better 25 work than the machines which have heretofore been produced, and in which the work may be introduced and removed with the minimum loss of time.

In shoe sewing machines of the McKay 30 type the work is engaged upon one side by the upper surface of the tip of the horn, and upon the other by a presser foot, which parts are relatively movable to accommodate work of varying thicknesses. The thread is laid 35 in the hook of the needle by a looping device or whirl located in the tip of the horn, and the needle during its retracting or loop-drawing stroke acts to tighten the preceding 40 stitch and to draw off thread from the supply for the formation of the next stitch. In order that the needle may be threaded properly, and in order that the stitches may be formed and tightened in a uniform manner in each cycle of operations of the machine, the needle must occupy substantially 45 the same position with relation to the horn at the end of its work piercing stroke, and must retract substantially the same distance from the work during each loop drawing 50 stroke, regardless of the thickness of the work. In machines of the McKay type at present in common commercial use, the horn is vertically fixed, and the presser foot is movable with relation to the horn to compensate 55 for varying thicknesses of work. In

these machines the limit of the work piercing stroke of the needle is fixed, while the loop-drawing stroke thereof is varied in accordance with changes in the vertical position of the presser foot, due to variations in the thickness of the work. Machines have been devised in which the presser foot is vertically fixed and the horn is arranged for vertical movement, and in these machines the needle retracts to the same position in each 60 cycle of operations, but its work piercing stroke is varied to compensate for variations in the position of the horn, due to changes in the thickness of the work. In commercial machines of the McKay type, the needle actuating mechanism has a provision for lost motion between limiting stops, the position of one of which is controlled by the presser foot so as to produce the necessary variations 65 in the needle stroke, and frictional devices 70 are employed to hold the needle stationary during the periods of lost motion. This mechanism has marked disadvantages, certain of which make it impracticable to run the machines at high speed. The abrupt engagement of the moving parts with the stops 75 causes objectionable vibration, noise and wear on the parts, especially when the machine is run at comparatively high speed. The frictional devices employed to hold the 80 needle stationary during the periods of lost motion are objectionable on account of the wear on the needle bar produced thereby which tends to throw the needle out of alignment with the whirl, and on account of the 85 heating of the needle bar, which often results when the machine is run at high speed, and also because of the loss of power incident to the employment of such devices. In 90 these machines the needle bar at the end of the loop-drawing stroke of the needle is controlled only by the engagement of the frictional devices therewith, and the needle is liable to overthrow and cause imperfect work, particularly when the machine is running at high speed. It has been a serious 95 problem in the manufacture of machines of the McKay type to devise a needle actuating mechanism of comparatively simple construction which would produce the necessary 100 variations in the needle stroke in a reliable manner which would be mechanically efficient, and which would operate at high speed without undue vibration, noise, friction or wear on the parts. Various needle actuating 105 devices have been proposed, but they have 110

mechanisms have been proposed, but such mechanisms have been for the most part complicated in construction, expensive to manufacture, and inefficient in the transmission of the power, or have been peculiarly subject to wear and consequent derangement.

One of the objects of the present invention is to provide machines of the McKay type with a needle actuating mechanism which is comparatively simple in construction and efficient in operation, which will produce the required variations in the stroke of the needle in a reliable manner, and which will operate smoothly even when the machine is run at high speed.

In accordance with this object, the invention contemplates a provision of an improved needle actuating mechanism comprising various novel and advantageous features clearly set forth in the following description and particularly pointed out in the claims.

The features of the invention will be readily understood from an inspection of the accompanying drawings taken in connection with the following detailed description.

In the drawings illustrating a machine embodying the invention in its preferred form, Figure 1 is a view in side elevation of the complete machine; Fig. 2 is a view in horizontal section, taken through the base of the machine; Fig. 3 is a view in front elevation, partly in section, of the head of the machine; Fig. 4 is a view in side elevation looking from the right, illustrating all except the rear portion of the head of the machine; Fig. 5 is a plan view, partly in section, of the portion of the machine shown in Fig. 4; Fig. 6 is a sectional view taken substantially on the line 6—6 of Fig. 4, looking in the direction of the arrows; Fig. 7 is a sectional view taken substantially on the line 7—7 of Fig. 4, looking in the direction of the arrows; Fig. 8 is a view in vertical section taken substantially in a plane through the axis of the main shaft of the machine, illustrating the forward portion of the head of the machine; Fig. 9 is a detail view, partly in section, illustrating particularly the variable clamp connection forming part of the presser foot lifting mechanism; Fig. 10 is a detail sectional view taken substantially on the line 10—10 of Fig. 8; Fig. 11 is a sectional view taken substantially on the line 11—11 of Fig. 10; Fig. 12 is a sectional view taken substantially on the line 12—12 of Fig. 4; Fig. 13 is a view in side elevation, partly in section, of the mechanism illustrated in Fig. 12, looking from the left; Fig. 14 is a sectional view taken substantially on the line 14—14 of Fig. 13; Fig. 15 is a sectional view taken substantially on the line 15—15 of Fig. 14; Fig. 16 is a detail view, partly in section, illustrating particu-

larly the mechanism by which the feed point is connected with its actuating mechanism; Fig. 17 is a detail sectional view illustrating the vibratory lever and co-operating locking bolt and certain devices for controlling the engagement of the locking bolt with the lever, all of which constitute parts of the stop mechanism; Fig. 18 is a view similar to Fig. 17, illustrating certain of the parts in different positions.

The machine illustrated in the drawings comprises the usual vertically reciprocating straight hook needle indicated at 1, which during each cycle of operations is projected through the work into position to receive the thread from a looping device located in the tip of the horn. The cast-off for preventing the previously formed loop from catching in the hook of the needle as the needle is retracted is indicated at 2. The work is supported during the sewing operation by the horn 3, which in the present embodiment of the invention is vertically fixed, but is arranged to rotate in the usual manner. The work is engaged between the upper surface of the tip of the horn and presser foot 4 which is arranged for vertical movement to accommodate work of varying thicknesses. The work is fed at intervals during the operation of the machine by the feed point 5, which is projected into the work and is then advanced in the direction of the seam to feed the work.

The presser foot 4 is secured to the lower end of a bar 5^a which is mounted to slide vertically in suitable guides on the frame. The lower portion of the presser foot bar slides in a guide in the forwardly projecting portion 4^b of the frame of the machine, and the upper portion of the bar 5^a is reduced to form a cylindrical extension or rod 6 which is arranged to slide in a sleeve 7 secured in an upwardly or forwardly extending bracket 8 on the frame. The presser foot is held down on the work by a heavy coiled spring 9 which surrounds the upper cylindrical portion of the presser foot bar, and engages at its lower extremity a shoulder on said bar, and at its upper extremity the lower end of the sleeve 7. The downward movement of the presser foot under the action of the spring 9, when no work is in the machine, is limited by a nut 10 threaded upon the upper end of the presser foot bar. By adjusting the nut 10 on the presser bar, the vertical position of the presser foot when no work is in the machine, and the tension of the spring 9, may be varied. The sleeve 7 is threaded into the bracket 8, and may be adjusted vertically to vary the vertical position of the presser foot when no work is in the machine without varying the tension of the spring 9. The sleeve 7 is held in adjusted position by a lock nut 12. By suitable adjustments of the nut 10 and the sleeve 130

7, the lower limiting position of the presser foot may be changed, and the tension of the spring 9 may be adjusted as required by the character of the work which is being operated upon.

As is usual in machines of this type, the presser foot is lifted during each cycle of operations to free the work from engagement with the upper surface of the horn and permit the work to be fed. It is evident that the vertical position of the presser foot when in engagement with the work varies with the thickness of the work, and in order that the presser foot may be lifted from the work substantially the same distance in each cycle of operations, regardless of its vertical position when in engagement with the work, a variable friction clamp connection is provided in the presser foot lifting mechanism, the relative positions of the parts of which are determined when the presser foot is down in engagement with the work, and which is locked during the lifting action of said mechanism. In the construction illustrated, the mechanism for lifting the presser foot comprises an arm 13 secured to a rock shaft 14 and provided at its extremity with a pivoted block 15 which engages in a suitable recess in the presser foot bar. The rock shaft 14 extends rearwardly substantially parallel with the main shaft of the machine, and a second arm 16 is attached to the rear extremity of said rock shaft. The arm 16 is provided with a recess or pocket 17 (see Fig. 9) at its extremity for the reception of a series of friction leaves 18. A series of friction plates 19 are arranged to slide through openings in the outer end of the arm 16, and are interfitted between the friction leaves 18. The ends of the friction plates 19 are pivotally connected with a lever 20 which is loosely mounted on the shaft 14, and carries a cam roll 21 which engages a cam groove 22 in the cam disk 23 mounted on the main shaft 24 of the machine. In order to clamp the friction plates 19 to the arm 16 so that they cannot move through said arm when the lever 20 is actuated, a lever 24^a is pivoted upon a transverse stud 25 carried by the arm 16, and is provided with a recess adjacent the end of the shorter arm in which engages a projection on the clamping plate 26 which fits in the pocket 17 and engages the face of one of the plates 19. The lever 24^a is actuated to force the clamping plate 26 inwardly in the pocket and clamp the friction plates 19 to the arm 16 by means of a coiled spring 27 (see Fig. 9) seated at one end in a recess or bore in the end of the shaft 14, and at the other in a recess in the end of the long arm of the lever 24^a.

During each cycle of operations, and while the presser foot is lifted, the lever 24^a is actuated to relieve the pressure upon the outer

friction plate 19, thereby unlocking the clamp and permitting the presser foot to be forced down on the work by the coiled spring 9. The unlocking of the clamp permits the friction plates 19 to automatically adjust themselves in the outer end of the arm 16 in accordance with changes in the vertical position of the presser foot due to variations in the thickness of the work. Before the presser foot is lifted, the clamp is again locked to connect the cam actuated lever 20 rigidly with the arm 16 to enable said lever to lift the presser foot. In the present invention, the lever 24^a is actuated positively to unlock the clamp. In the construction illustrated, the end of the longer arm of the lever 24^a is recessed to receive one extremity of a strut 28, the other end of which strut is received in a similar recess in the end of a screw 29 threaded into an arm 30 of a lever pivoted on a stud 31. Said lever is provided with a second arm 32 which carries a cam roll 33 which operates in a cam groove 34 in a cam disk 35 secured to the main shaft 24 of the machine. The provision of the spring 27 for actuating the lever 24^a to lock the clamp insures the actuation of said lever sufficiently to lock the clamp at all times when the lever is free to move under the action of the spring, and no readjustment of the parts is necessary even when they have become worn by use. The screw 29 is adjusted so that the lever 24^a is actuated to an extent somewhat greater than that required to unlock the clamp, thereby eliminating the necessity of frequent readjustment to compensate for wear on the parts. The provision of the series of friction leaves and an interfitting series of friction plates for the clamp, furnishes a large extent of engaging friction surfaces, and enables the clamp to be locked securely with a comparatively light pressure upon the lever 24.

As shown in Fig. 9, the hub of the lever 20 is confined between the arm 16 and an adjacent portion of the frame which forms a bearing for the shaft 14. To take up wear and prevent lateral play of said lever on the shaft, the lever is provided with a bearing sleeve 36 threaded into the hub of the lever, which may be adjusted when the parts become worn.

In order to enable the operator to lift the presser foot so that the finished work can be removed, and another piece of work inserted in the machine, or so that the work being operated upon can be adjusted, a lever 37 is pivoted upon a stud 38, and carries a roll 39 at its extremity which engages beneath a projection 40 on the arm 16. The other extremity of said lever is connected by means of a treadle rod 41 with a lever 42 located in the base of the machine which is operated from a treadle 43.

The needle 1 is secured by means of a

clamping collar 43^a in the lower end of the needle bar 44 which is mounted to reciprocate in guides in the plate 4^a and in the forwardly projecting bracket 44^a formed in the frame of the head of the machine. As above stated, in the present embodiment of the invention, the work support or horn is vertically immovable, and the vertical position of the presser foot varies as the work varies in thickness. The mechanism for actuating the needle operates to project the needle through the work into substantially the same limiting position in each cycle of operations and to vary the retracting or loop drawing stroke of the needle in accordance with changes in the thickness of the work, so that the needle always retracts substantially the same distance from the work, and is constructed and arranged to produce these variations in the needle stroke while maintaining the needle at all times under positive control. The needle bar is reciprocated by the oscillatory movements of a lever 45 mounted on a shaft 46 supported in bearings in the frame of the machine, said lever having an arm 47 provided with a forked extremity which embraces the upper end of the needle bar. The arm 47 is connected with the upper end of the needle bar by means of blocks 48 mounted on pins 49 journaled respectively in the forks at the extremity of the arm 47, said blocks being arranged to operate in grooves in a block 50 secured to or formed integral with the upper end of the needle bar. The lever 45 is provided with a pair of parallel arms 51 which extend over the main shaft 24 of the machine, and are connected by a bolt 52 on which is journaled a block 53. The block 53 is arranged to operate in an arc shaped slot in a transversely vibrating bar or link 54 supported upon connecting rods 55 and 56 pivotally connected with said link at each side of the longitudinal center thereof. Two connecting rods 56 identical in construction, arrangement and mode of operation, are provided to furnish a firm supporting structure for the link 54. The inner or lower end of the connecting rod 55 embraces a crank 57 on the main shaft of the machine, and the lower end of each of the connecting rods 56 embraces a crank 58 on said shaft, said crank being arranged at a greater distance from the axis of the main shaft, or having a greater throw than the crank 57. The cranks 57 and 58 are preferably arranged on the same side of the axis of the main shaft, and in such positions that their axes both intersect a line intersecting the axis of the main shaft. With this construction, during the rotation of the main shaft of the machine the bar 54, as a whole, is transversely vibrated by the independent transverse vibratory movements imparted to the ends of the bar through the connecting rods 55 and 56, and oscillates the lever 45 which imparts reciprocatory movements to the needle bar. The vibratory movements imparted to the respective extremities of the bar differ in amplitude because of the difference in the throws of the cranks 57 and 58. By swinging the bar or link 54 about its connection with the main shaft 24, the position of the block 53 in the slot in said link will be changed, and on account of the difference in the amplitudes of vibration of the respective ends of said link, the extent of the oscillatory movements of the lever 45 and of the reciprocatory movement of the needle bar will be varied. The slot in the link 54 is so constructed and the parts are so arranged that when the needle is at the limit of its downward or work piercing stroke, the swinging of the link 54 about its connection with the main shaft would produce substantially no movement of the lever 45, and therefore would not affect the position of the needle. This result is secured by forming the slot substantially parallel with the path or line which would be described on the link by a fixed point if the link were swung about its connection with the shaft when the parts are in the positions which they assume at the end of the work piercing stroke of the needle. The limit of the retracting stroke of the needle will therefore be varied by varying the position of the link 54 about its connection with the main shaft while the limit of its work piercing stroke will be unchanged. When the link 54 is positioned so as to locate the block 53 in the right hand end of the slot (Fig. 6), the needle bar will be given its minimum retracting stroke. When the link 54 is adjusted so as to place the block 53 at the left hand end of the slot in the link, the maximum retracting stroke will be imparted to the needle bar. When the link is adjusted so that the block 53 is in an intermediate position in the slot, the needle bar will be retracted to an extent between its minimum and maximum limits, depending on the relative positions of the link and block. It is to be noted that the connections between the main shaft and the lever 45 as above described are very efficient in the transmission of motion to said lever. At whatever point the block 53 may be located in the slot in link 54, that portion of the link in immediate engagement with the block will be moved very nearly in the direction of movement of said block, so that there is very little power lost in transmission of motion to the lever 45.

In order that the vertical or loop drawing stroke of the needle may be changed in accordance with changes in the thickness of the work, a connection is provided between the presser foot and the link 54 which acts to swing said link about its connections.

with the main shaft when a change occurs in the vertical position of the presser foot, due to a variation in the thickness of the work. To this end a pair of links 58^a are 5 pivotally connected at their forward extremities with the link 54, and at their other extremities are both connected with a head 59 formed on an arm 60 of a lever 61 pivoted loosely on the shaft 14. The lever 61 is provided with a laterally extending arm 62, the lower face of which engages the upper face of an arm 63 fast on the rock shaft 14. The faces of the arms 62 and 63 are normally held in engagement by a coiled 10 spring 64 surrounding a bolt 65 passing through both arms, said spring engaging at its respective extremities the arm 62 and a nut on said bolt. Through the connection of the arm 13 fast on the shaft 14 with the 15 presser foot bar, the angular position of said shaft is determined by the position of the presser foot. When the presser foot rises or falls, the shaft 14 is rotated and the arm 63 is swung about the axis of the 20 shaft. If the link 54 and the mechanism described connecting said link with the arm 63 were free to move when a change occurred in the vertical position of the presser bar, the link 54 would be turned about its 25 connections with the main shaft during the 30 vertical movement of said bar.

In the illustrated embodiment of the invention the operating position of the link 54 for the next advancing and retracting 35 strokes of the needle is determined while the presser foot is down in engagement with the work and the work held between the presser foot and horn, and mechanism is provided for locking the link 54 in this position 40 while the presser foot is lifted so that it is unaffected by the vertical movement of the presser bar at such time. The locking mechanism for the link 54 is unlocked just before the presser foot descends upon the 45 work, so that the position of the link 54 may be determined by the position of the presser foot when it has engaged with the work. In the construction illustrated, the lever 61 is provided with an upwardly extending arm 66 to which is pivotally connected a slide 67 operating in a suitable 50 guide in the frame of the machine. Any convenient form of connection may be provided between the arm 66 and the slide 67 to 55 accommodate the rectilinear movement of the slide and the swinging movement of the arm. A roll clutch mechanism is provided for locking the slide, said clutch mechanism comprising clutch rolls 68 engaging the rear 60 face of the slide, and yieldingly pressed forward in a direction angular to the slide by spring actuated plungers 69. The clutch rolls are actuated to unclutch the slide by means of a pin 70 mounted to slide in a bore 65 in the frame, and provided with a pointed

extremity which engages between the rolls 68. The pin 70 is provided at its outer end with a head in which is mounted a roll 71 which engages a face cam formed on the cam disk 23. The roll is held in engagement with the cam disk by means of springs 72 acting against the head of the pin 70.

During the retracting stroke of the needle, and while the presser foot is being lifted, the slide 67 is locked by the clutch, 75 thereby preventing the link 54 from being swung about its connection with the main shaft. The lifting of the presser foot while the slide 67 is locked, causes the arm 63 to swing away from the arm 62, the spring 64 being compressed by the relative movement of said arms. Just after the needle has reached the limit of its upward stroke, the variable friction clamp of the presser foot lifting mechanism is unlocked, permitting 80 the presser foot to be forced down upon the work by the coiled spring 9. Almost simultaneously with the unlocking of the presser foot friction clamp, the slide 67 is unlocked, the arms 62 and 63 are brought 85 into engagement, and their angular positions determined by the vertical position of the presser foot when it has engaged with the work. In case any change has occurred in the thickness of the work since the last stitch 90 was formed, the change in the position of the arm 63 will have caused the arm 62 of the lever 61 to swing about the shaft 14, and through the connections of said lever with the link 54, will have caused said link 100 to swing about its connection with the main shaft of the machine to vary the next upward stroke of the needle.

The machine is provided with the usual 105 cast-off for preventing the barb of the needle from catching in the previously formed loop as the needle is retracted out of engagement with the work. The cast-off is mounted to slide in a suitable groove in the needle bar, and is attached at its upper end to a block 73 which slides between the needle bar and the opposed portion of the presser foot bar. The block 73 is arranged to slide 110 between limiting stops on a bar 74 which is provided with a slot 75 to receive a sleeve 115 76 mounted on a bolt 77 secured in the needle bar. The block 73 is held against the lower stop on the bar 74 by a spring 78 which permits the cast-off to yield when its end comes into engagement with the work. 120 The bar 74 is connected at its upper end by means of links 79 and 80 with the arm 81 of a friction device which comprises a disk 82 to which said arm is attached, a fixed disk 83, a pad of friction material 84 between said disks, and a coiled spring 85 surrounding a bolt passing through the disks and interposed between the outer face of the disk 82 and a nut threaded on the end 125 of the bolt.

The feed point 5 of the machine is mounted upon a slide 86 arranged in an opening in the lower end of the presser bar. The lower face of the forwardly extending portion of the slide 86 in which the feed point is secured is inclined, and engages the adjacent inclined faces of the presser bar and presser foot, as clearly shown in Figs. 3 and 10. The slide 86 is U-shaped in section, as shown in Fig. 11, and its sides embrace the lower end of an L-shaped slide 87, the vertical arm of which slide is arranged in a groove in the presser bar, and is held in place in said bar by the adjacent portion of the frame through which the presser bar slides. A horizontal slot 89 is formed in the slide 87 and cam slots 90 are formed in the portion of the presser bar which embrace the slide 86 and the slide 87. The slide 86 and the slide 87 are connected with each other and with the presser bar by means of a bolt or pin 91 fixed in the slide 86, which engages in the slot 89 in the slide 87 and in the cam slots 90 in the presser bar. The feed point is actuated through an oscillatory arm 92 connected with the bolt 91 by means of links 93. Each of the slots 90 is constructed so that the right-hand portion thereof is inclined at a considerable angle to the horizontal or to the surface of the work, and so that the left-hand portion thereof is very nearly horizontal but inclined downwardly slightly in the direction of the feed movement of the work. During the forward movement of the feed point, the angular position of the feed point is maintained substantially unvaried by the engagement of the surface 94 of the slide 86 with the lower horizontal surface of the slide 87, said surfaces being held in engagement during the advancing movement of the slide 86 by a tension spring 95 connecting the rear end of the slide 86 with the end of the arm 92. Starting with the feed point in retracted position out of engagement with the work, as shown in Figs. 3 and 10, as the slide 86 is carried to the left by the lateral swinging movement of the arm 92, the feed point is first moved downwardly at an angle by the movement of the bolt 91 through the sharply inclined portions of the cam slots 90, and is thus projected into engagement with the work. While the bolt 91 is moving through the left-hand or slightly inclined portion of the slots 90, the feed point acts to feed the work, and on account of the slight inclination of said slots, the feed point is projected slightly farther into engagement with the work as it advances, which insures certainty and reliability in the feeding action. During the entire movement of the feed point from retracted position out of engagement with the work, to its limiting position in the direction of feed, it is maintained in unvaried angular posi-

tion by the engagement of the slides 86 and 87, the slide 87 moving vertically in its guides to compensate for the vertical movement of the slide 86 during the advance of the feed point. On account of the structure of the cam slots 90 as described, the slide 86 is not lifted away from the work during the retracting movement of the feed point, until the bolt 91 reaches the sharply inclined portion of the cam slots, which occurs toward the end of the retracting stroke of the feed point. In order to permit the feed point to be drawn back without undue resistance, the connection between the slide 87 and the slide 86 is arranged to permit the slide 86 to swing about the connecting bolt 91 as the slide 86 is retracted. To this end the slide 86 is cut away at 96 at an angle to the adjacent horizontal face of the slide 87. As the slide 86 is drawn back after the feeding movement of the feed point by the backward pull of the links 93 on the bolt 91, the resistance of the work against the feed point will cause the slide 86 to swing about the bolt 91 against the tension of the spring 95. The feed point will drag back over the surface of the work until the bolt 91 reaches the sharply inclined portion of the cam slots 90, when the slide 86 and the slide 87 will be lifted to bring the feed point out of engagement with the work and the parts will be restored to the positions shown in Figs. 3 and 10.

The whirl or looping device located in the tip of the horn is driven from the main shaft 24 through a series of shafts connected by suitable gears and operated from the gear 97 mounted on the main shaft 24. The thread leading from a container 98 is conducted down into the wax pot about a thread truck 99 located therein, through a stripper 100 mounted on the cover of the pot, and from thence passes upwardly through the base of the horn over a tension device mounted upon the base of the horn, and from the tension device over a series of thread trucks within the horn to the looping device.

During the sewing operation, the machine is driven by means of a belt 122 passing about a pulley 123 fast on the main shaft 24 of the machine, and connecting said pulley with a pulley 124 mounted upon a driving shaft 125 located in the base of the machine. The shaft 125 is provided with a loose pulley 126 and with a pulley 127 splined thereto but movable longitudinally thereof, which is driven by a belt from the power shaft. The pulley 124 is loosely mounted on the shaft 125 in front of the pulley 127, and is provided with a ring 128 of friction material for engagement with the adjacent surface of the pulley 127. A fourth pulley 129 is pinned to the shaft 125, and the pulley 124 carries a second ring 130

of friction material for engagement with the adjacent surface of the pulley 129. The shaft 125 is arranged for longitudinal movement in its bearings, and when said shaft is 5 thrust endwise toward the rear of the machine, the pulley 124 is clutched between the opposed faces of pulley 129 and pulley 127 and thereby caused to rotate with said pulleys. When the shaft is released and allowed to move forwardly or toward the 10 front of the machine, the loose pulley 124 is carried out of clutching engagement with the pulleys 127 and 129. The shaft 125 is actuated to clutch the pulley 124 between pulleys 127 and 128 by suitable connections 15 from the treadle 43. Said connections comprise a bell crank lever pivoted on a stud 131 and provided with an arm 132 which engages the end of the shaft 125. The other arm 132^a of the bell crank lever is provided 20 with a forked forward extremity which embraces a rod 133, which is the rod which controls the device for throwing the stop mechanism into operation. The rod 133 is connected at its lower end with a lever 134, which lever is arranged to be actuated from the treadle. A collar 135 is secured to the rod 133 above the arm 132^a, and the rod 133 is yieldingly held in raised position by 25 the coiled spring 136. The treadle 43 is pivoted on a horizontal stud 137 carried by a block mounted on a vertical swivel pin 138. This manner of mounting the treadle permits the treadle to be swung vertically and 30 horizontally. The rearwardly extending arm 139 of the treadle is provided with a lateral projection 140 which is adapted to engage beneath the forward end of the lever 134. When the projection 140 is beneath the 35 arm of the lever 134, and the treadle is depressed, the rod 133 is moved downwardly and actuates the bell crank 132 to thrust the shaft 125 rearwardly and thereby clutch the pulley 124 to the shaft and start the machine 40 into operation. When the forward end of the treadle is released, it is lifted by a coiled spring 141, allowing the rod 133 to be lifted by the spring 136 to release the lever 132—132^a. The shaft may then move forward to 45 release the pulley 124 from clutching engagement with pulleys 127 and 129. The rearwardly extending arm of the treadle is provided with a second projection 142 for engagement beneath a forwardly extending 50 arm of the lever 42 by which the presser foot is lifted. The lateral movement of the arm 139 of the treadle is limited by the engagement of the end of the arm with stops 143 and 144. These stops are so placed that 55 when the treadle is swung horizontally to bring the end of the arm 139 into engagement with the stop 143, the projection 140 will be brought beneath the lever 134, and the projection 142 will be away from beneath the lever 42, and when the treadle is 60

swung in the opposite direction to bring the end of the arm 139 into engagement with the stop 144 the projection 142 will be brought beneath the lever 42, and the projection 140 will be away from beneath the 70 lever 134. To prevent the actuation of the treadle when the treadle is in an intermediate horizontal position in which the projections 140 and 142 might both be in position to engage respectively levers 134 and 42, a 75 forwardly projecting lug 144^a is formed on the bracket which supports the levers 134 and 42 between the stops 143 and 144.

In order to permit the work to be removed when the seam has been completed, 80 and another piece of work to be introduced easily and quickly, the machine is provided with mechanism for automatically arresting the rotation of the shaft at the point in the cycle of operations when the needle is retracted out of engagement with the work and the presser foot is free to be lifted. When the treadle is released at the end of the sewing operation, the mechanism which 85 brings the machine to rest with the parts 90 in proper positions for the removal of the shoe is thrown into operation. This mechanism comprises a friction clutch, one member of which is driven at slow speed in a forward direction, and which, when the 95 clutch members are engaged, first acts as a brake to slow the shaft down to the slow speed of the forwardly driven member, and then to drive the shaft at slow speed in a forward direction to bring the devices which 100 finally arrest the rotation of the shaft into engagement. The friction clutch consists of clutch members 145 and 146, of which the member 145 is loosely mounted on the main 105 shaft 24 of the machine, and is driven at 110 slow speed in the same direction as the normal direction of rotation of the shaft 24, by means of a spiral pinion 148, mounted on a hollow shaft or sleeve 149 journaled in bearings 150 in the machine frame, which 115 meshes with the teeth of a spiral gear 147 secured to or formed integral with the clutch member 145. The hollow shaft 149 is constantly driven during the rotation of the main shaft of the machine through a friction clutch connecting said shaft with a pulley 151 which is continuously driven by 120 means of a belt 151^a connecting said pulley with the pulley 129 mounted on the shaft at the base of the machine. The clutch connection between the shaft 149 and the pulley 151 consists of a clutch member 152 secured to or formed integral with the shaft 149, and a second clutch member 153 carried 125 by the pulley 151. The pulley 151 is journaled upon a rod or shaft 154 extending through the hollow shaft 149, and is confined between collars carried by the rod, as clearly shown in Fig. 14. The clutch members 152 and 153 are engaged and disen- 130

gaged by the longitudinal movement of the rod 154 within the hollow shaft 149, as will be presently explained. A brake is provided to arrest the rotation of the shaft 149 and 5 the pinion 148 when the clutch connecting said shaft with the pulley 123 is disengaged. This brake comprises a friction brake member 155 mounted on the shaft 149 to rotate with said shaft. The brake member 155 is 10 connected with the hollow shaft by a pair of blocks or keys 155^a secured by screws to the member 155 and arranged to project inwardly through slots 156 in the adjacent portion of the hollow shaft. The brake member 155 is arranged to be engaged with the interior of a brake shoe 157 formed on the frame of the machine when the rod 154 is moved in a direction to disengage the clutch. The inner ends of the blocks 155^a 15 20 extend inwardly to points adjacent to the reduced portion 158 of the rod 154, and the brake member 155 is normally held in position on the rod with the blocks 155^a in engagement with the shoulder 159 by a coiled spring 160 surrounding the reduced portion 25 of the rod 154, and engaging the member 155 outside of the hollow shaft 149, said spring being confined between the member 155 and a collar or washer 160^a held by a 30 nut threaded on the end of the rod. The members of the friction clutch are held normally in engagement by means of a second coiled spring 161 surrounding the reduced portion 158 of the rod, and arranged within 35 the coiled spring 160. The coiled spring 161 engages at its inner end the projecting extremity of the hollow shaft 149, and acts to maintain the members 152 and 153 of the friction clutch normally in engagement, and 40 the brake member 155 normally disengaged from the brake shoe. In order to disengage the clutch and engage the brake, the rod 154 is moved longitudinally to the left (Fig. 14). This movement of the rod compresses 45 the coiled spring 161, but does not affect the coiled spring 160 until the friction clutch is disengaged and the members of the brake are brought into engagement, since the spring 160 holds the blocks 155^a against the 50 shoulder 159, and the brake member 155 moves with the shaft 154. Further longitudinal movement of the rod, however, after the brake is engaged, causes the compression of both the spring 160 and the spring 55 161, these springs then serving to engage the members of the brake with considerable pressure. When the rod is released, the springs act together to carry it back in the opposite direction until the shoulder 159 on 60 the rod engages the inner ends of the blocks 155^a, after which, by the force of the spring 161, the brake member 155, rod and spring 160 are moved to the right together a slight distance, sufficient, however, to disengage 65 the brake and engage the clutch.

The clutch member 145 is secured to and preferably formed integral with a sleeve 162 mounted loosely on the main shaft 24 of the machine, and extending from said clutch member toward the end of the shaft. The 70 clutch member 146 is secured to a flange 163 extending outwardly from a sleeve 164 loosely journaled on the sleeve 162. The sleeve 164 is free to move longitudinally of the sleeve 162 and of the shaft 24, but is 75 caused to rotate with the shaft by a connection with the pulley 123. In the construction illustrated, the sleeve is provided with a pair of spaced shoulders or abutments 165, which receive between them an arch-shaped 80 lug 166 on the pulley 123. The sleeve is normally held in position longitudinally of the shaft with the clutch members out of engagement by means of a coiled spring 167 surrounding a bolt 168 passing through a 85 hole in the pulley 123 and secured in the sleeve 164, said spring being seated in a recess in the pulley 123, and acting against the head of the bolt.

When the clutch members are engaged, 90 the member 145 at such time being rotated at slow speed in a forward direction, they first act as a friction brake to slow down the speed of the main shaft until the shaft and the parts rotating therewith are moving at 95 the same speed as the member 145. The member 145 then acts as a driving member through its engagement with the clutch member 146 to drive the shaft in a forward direction until the devices which finally 100 bring the shaft to rest are brought into engagement. The clutch members are engaged at a definite point in a rotation of the shaft, and the shaft is finally brought to rest at the end of a definite interval after the clutch 105 members are engaged. The mechanism for engaging the members 145 and 146 of the clutch comprise a timing cam consisting of a cam groove 170, formed in the sleeve 164 and engaged by a cam roll 171 carried by an 110 arm 172 of a bell crank lever pivoted on a shaft 173. The other arm 174 of the bell crank is provided with a recess 175 adapted to receive a projection 176 at the upper end of a locking pin 177 which is normally held 115 out of engagement with the arm 174, so that during the normal operation of the machine, the bell crank lever is oscillated idly by the cam. The locking pin 177 is mounted to slide vertically in the forward end of a slide 120 178 mounted to slide horizontally in suitable guides in the frame, and yieldingly held in forward position by a coiled spring 179 interposed between a shoulder on the slide and the end of a screw 180 threaded into the 125 frame, by which the tension of the spring may be adjusted. The slide is provided with an extension 181 projecting rearwardly therefrom through a suitable perforation in the portion of the frame in which the slide 130

is mounted, and the forward movement of the slide in its guides is limited by a nut 182 threaded on the extension 181. By adjusting this nut, the slide may be adjusted to bring the locking pin into a position such that the projection 176 on the locking pin will register with the recess 175 at the proper time in the rotary movement of the main shaft. The locking pin is forced upwardly in the slide by a coiled spring 183 seated in a recess in the slide 178 and engaging the head of the locking pin, and the lower end of the pin is connected with the treadle rod 133 so that the pin is held down with the projection 176 out of engagement with the recess 175 while the treadle is depressed and the main driving clutch engaged to drive the main shaft of the machine.

When the projection 176 on the locking pin engages the recess 175 in the arm of the bell crank lever, the lever is no longer free to oscillate, since it is locked to the slide 178, and by the action of the face of the cam groove 170 on the roll 171 carried by the arm of said lever, the clutch member 146 will be forced over into engagement with the clutch member 145 when the roll engages a certain point in the cam groove, which occurs at a definite point in the rotation of the main shaft. After the clutch members have been engaged, the slide 178 will be moved rearwardly in its guides against the tension of the spring 179 by the action of the cam groove 170 on the bell crank lever, and the force with which the clutch members are engaged will depend upon the tension of the spring 179.

The treadle rod 133 is connected with an arm 181 pivoted on a stud 185 mounted in a block 186 secured by a pin 187 to the lower end of the locking pin. A latch 188 is also pivoted on the stud 185, and is arranged to engage beneath a shoulder 189 on the slide 178 and hold the locking pin from upward movement until the treadle rod has been raised sufficiently to leave the locking pin free to move upward into secure locking engagement with the recess in the arm of the bell crank lever. The latch is disengaged from the shoulder by the movement of the arm 181, due to the lifting of the treadle rod. A lost motion connection is provided between the arm and the latch to allow the treadle rod to be raised before the latch is disengaged from the shoulder 189. In the construction illustrated, the connection between the arm and the latch consists of a pair of shoulders formed on the hub of the arm adapted to engage corresponding shoulders on the hub of the latch. These shoulders are arranged so that when the arm is moved in either direction there is a certain amount of lost motion of said arm before the latch is actuated by the arm. When the treadle is depressed, the arm 181 swings

down until one of the shoulders on its hub engages the opposed shoulder on the hub of the latch, after which the continued downward movement of the treadle acts to draw the locking pin down against the tension of the spring 183. During this movement of the locking pin the latch 188 slides down along the outer face of the shoulder 189 and finally snaps in beneath said shoulder. When the treadle is released, the treadle rod first moves upwardly, swinging the arm 181 upwardly therewith without affecting the locking pin until the shoulder on the hub of the arm 181 engages the opposed shoulder on the hub of the latch 188. The latch 188 is then swung outward from beneath the shoulder 189, leaving the locking pin free to be forced upward by the spring 183.

Mechanism is provided for timing the engagement of the locking pin with the arm 174 of the bell crank lever, so that the locking pin will not move into engagement with said arm until the arm is in a position substantially such that the recess 175 registers with the projection on the locking pin. This insures a secure locking engagement between the locking pin and the arm. This mechanism is illustrated particularly in Figs. 17 and 18. The block 186 extends upwardly along the end of the slide 178, and a second block 190 is pivoted to the block 186 on a stud 191. The block 190 is forced in a direction to bring the said block up against the end of the slide 178 by a spring 192 coiled about the stud 191 and engaging a pin 193 secured in the block 190. A third block 194 is pivoted on a stud 195 at the upper end of the block 190, and is normally held down against the upper end of the block 190 by a spring pressed pin 196, the pointed extremity of which engages a recess in said block. When the locking pin is drawn down by the depression of the treadle, the block 190 is swung outwardly away from the end of the slide 178 by the engagement of a shoulder 197 on the forward end of the slide with a shoulder 198 on the block 190. When the latch 188 is released from beneath the projection 189, and the locking pin is forced upward by the spring 183, the shoulder 198 is disengaged from the shoulder 197, and the block 190 swings inwardly under the influence of the spring 192 and brings up against the end of the slide. The block 190 is provided with a shoulder 199 which is adapted to engage beneath a shoulder 200 formed on the forward end of the slide 178, when the block 190 is swung inwardly into engagement with the slide. The engagement of the shoulder 199 with the shoulder 200 prevents the locking pin from being forced upwardly while they are engaged. The block 194 projects above the upper face of the slide 178, and the arm 174 of the bell crank lever operates close to the upper face of the slide.

When the arm 174, during the oscillatory movement of the bell crank lever, arrives in a position such that the recess 175 registers with the projection 176, the lever strikes the inner face of the block 194 and knocks said block and the block 190 on which it is mounted, away from the end of the slide, thereby disengaging the shoulders 199 and 200, and permitting the locking pin to be forced upwardly to engage the projection 176 in the recess 175.

When it is desired to stop the machine without throwing the stop mechanism into operation, the block 194 may be swung about its pivotal connection with the block 190 by a manipulation of the arm 201 formed on said block, the block then being held in position by the engagement of the pin 198 in a second recess in the block. When the block has been thus adjusted it will be out of the path of the arm 174 of the bell crank lever when the block 190 swings in against the end of the slide to bring the shoulder 199 beneath the shoulder 200. The engagement of these shoulders will prevent the locking pin from being forced upward into locking engagement with the arm 174 of the bell crank lever, and the machine is then allowed to slow down gradually until it comes to rest.

30 The cam groove 170 is preferably timed so that the arm 174 of the bell crank lever is moved into a position to bring the recess 175 into registration with the projection 176 just as the roll 171 arrives at an idle portion 35 of the cam groove, thereby allowing the shaft to rotate a certain interval after the projection 176 is engaged in the recess 175, before the clutch members are engaged. This permits the projection 176 to become 40 firmly seated in the recess 175 before the cam acts to engage the clutch members.

After the slow speed clutch members 145 and 146 are engaged and the shaft has been slowed down to the speed of the slow speed 45 driving member 145, and while it is being driven at slow speed in a forward direction by said member, the stopping devices which finally bring the shaft to rest are brought into engagement. One of these devices is 50 carried by one of the driven parts, and the shaft is disconnected from the driving mechanism and its rotation arrested by mechanism which is actuated by the movement of the positively driven stopping device. The clutch members 145 and 146 are 55 still engaged when the main shaft is brought to rest, and the rotation of said shaft is arrested by disengaging the clutch which connects the hollow shaft 149 with the pulley 60 151 and engaging the brake member 155 with the brake shoe 157 to stop the rotation of said shaft and the pinion 148. The stopping devices through the engagement of 65 which the main shaft is finally brought to rest comprise a finger or shoulder 463 car-

ried at the forward end of an arm 202 and adapted to be engaged by a projection or lug 204 secured to or formed integral with the flange 163. The arm 202 is mounted for movement to carry the finger 203 into and out of the path of the lug 204, and to this end is secured to a rock shaft 205 journaled in an arm 206 which is pivoted on a shaft 207. When the locking pin is in lowered position with the projection 176 out of engagement with the recess 175, the arm 202 is held down so that the shoulder 203 is out of the path of the projection 204 by a block 208 secured to the lower end of the locking pin, which engages a roll 209 carried by an arm 210 secured on the rock shaft 205. When the locking pin is forced upward to engage the projection 176 in the recess 175, the arm 202 is swung upwardly to bring the shoulder 203 into the path of the lug 204 by a tension spring 211. The arm 206 which is pivoted on the shaft 207 extends downwardly in position to engage the end of the rod 154. When the lug 204 engages the shoulder 203 on the arm 202, it carries the arm 202 to the left (Fig. 12), thereby swinging the arm 206 to the left about the shaft 207 and engaging the end of the arm 206 with the end of the rod 154. The rod 154 is thereby thrust longitudinally against the tension of the spring 161 in a direction to disengage the clutch members 152 and 153, and to engage the brake member 155 with the brake shoe 157. After the brake is engaged further movement of the shaft 154 takes place against the tension of both the springs 160 and 161, thereby forcing the brake members more firmly into engagement. The springs 160 and 161 cushion the action of the stopping devices so that the parts are brought to rest without shock or jar and without excessive strain on any of the parts. When the forward rotation of the shaft has been arrested, the parts are securely locked together, thereby preventing recoil.

It will be obvious that the lug 204 will engage the projection 203 at the end of a definite interval after the members of the slow speed clutch are engaged, and the main shaft will be stopped at a definite point in its rotary movement. The cam groove 170 and the lug 204 are relatively arranged so that the interval between the engagement of the members of the slow speed clutch and the engagement of the stopping devices is sufficient to insure that the shaft will be slowed down to the speed of the driving member of the slow speed clutch and will be driven thereby at slow speed before the stopping devices are engaged.

In order to prevent breakage of the parts in case the stop mechanism fails to act properly and the shaft is not slowed down to the speed of the driving member of the slow

speed clutch when the lug 204 engages the projection 203, a projection 211^a is formed on the arm 202 and is provided with an inclined face 211^b. If the shaft and the parts 5 rotating therewith are moving at a higher speed than the speed of rotation of the slow speed driving clutch member when the lug 204 engages the projection 203, the arm 202 will be carried over farther to the left than 10 under normal conditions, and the inclined face of the projection 211^a will be brought into engagement with an inclined face 211^c on the frame, and the arm 202 will be thrown down so as to disengage the projection 203 from the lug 204 and allow the shaft to make any other rotation before it comes to rest.

In the illustrated embodiment of the invention, the parts are so timed that the members of the braking and slow speed forward driving clutch are engaged while the needle is retracting out of engagement with the work, and the stopping devices are arranged to bring the shaft to rest when the needle is 20 near the limit of its upward stroke, and when the shaft is in a position such that the parts of the needle actuating mechanism which act to vary the reTRACTING stroke of the needle and of the variable friction clamp 25 of the presser foot lifting mechanism are unlocked, which occurs after the needle has completed its loop drawing stroke and has just started to descend. This is the position of the parts most suitable to permit the 30 removal and introduction of work, since the presser foot may be lifted freely by the actuation of the treadle. The descent of the needle a slight distance from the the limit of its reTRACTING stroke before the machine 35 is brought to rest is of advantage, since the needle loop is thereby slackened slightly and may be more easily severed. After the 40 seam has been completed and the machine brought to rest, the operator severs the leg 45 of the needle loop which leads to the work. At that point in a cycle of operations at 50 which the needle is reTRACTED out of engagement with the work and near the limit of its reTRACTING stroke, and the parts of the 55 presser foot lifting mechanism and of the needle stroke varying mechanism are unlocked, the feed point is down in work engaging position adjacent the needle loop, and interferes with the severing of the 60 thread of the loop. In order to bring the feed point into a position such that it does not interfere with the severing of the thread when the machine is brought to rest, the 65 present invention comprises means for with- 70 drawing the feed point from its normal position in a direction away from the needle upon stopping the machine. In the present 75 construction, the feed point is automatically disconnected from its actuating mechanism 80 upon stopping the machine, and is imme- 85

ately drawn back into a retracted position upon being disconnected from its actuating mechanism. The arm 92 through which the feed point is actuated is connected by a link 213 with an arm 214 secured to a shaft 215 70 journaled in a bearing in the machine frame. A second arm 216 is secured to the shaft 215, and carries a cam roll engaging a cam groove in the cam disk 23. The connection between the link 213 and the arm 214 is arranged so that the link may be disconnected from the arm. To this end the arm 214 is provided with a cylindrical housing in which is arranged a plunger 218 having a tapered head 219 adapted to engage in a 80 suitably tapered hole in the end of the link 213. The head of the plunger is normally held in engagement with the hole in the link by a coiled spring 220 surrounding the plunger and interposed between the head of 85 the plunger and a cap 221 screwed on the inner end of the cylindrical housing. The link 213 is disconnected from the arm 214 by drawing back the plunger 218 against the tension of the spring 220. In the present embodiment of the invention, the plunger 218 is automatically actuated by the engagement of the stopping devices which finally bring the shaft to rest, to disconnect the link from the arm. The mechanism for 90 actuating the plunger from the stopping devices comprises a slide 222, to the forward extremity of which is secured a forked bracket 223 which receives the shank of the plunger 218, and is interposed between the 100 end of the cap 221 and a collar 224 on the plunger. The slide 222 extends substantially parallel with the main shaft to the back of the machine, and at its rear end is provided with a recess which receives the 105 end of an arm 225 fixed on a shaft 226. Another arm 227 fixed on said shaft is arranged to engage the end of a slide 228. The slide 228 extends across the machine, and its other extremity projects into position, 110 to be engaged by a shoulder 229 on the arm 206. When, upon stopping the machine, the arm 206 is swung to the left (Fig. 12), through the engagement of the lug 204 with the projection 203, the shoulder 229 on said 115 arm engages the end of the slide 228 and carries said slide to the left therewith. This movement of the slide 228 actuates the arm 227, shaft 226 and arm 225 in a direction 120 to retract the slide 222, and to withdraw the head of the plunger 218 from the hole in the link 213. When the link 213 has been thus disconnected from the arm 214, the feed point is immediately drawn back into re- 125 tracted position on the presser foot by a spring 230 which engages the end of the link 213.

When the machine is started, the arm 206 is thrown back by the springs 160 and 161, releasing the slide 228 and the mechanism 130

connecting said slide with the plunger 218, and allowing the forward end of the plunger to be forced against the inner face of the link 213. When the movement of the arm 214 brings the head of the plunger into registration with the hole in the link 213, the head of the plunger snaps forward into the hole in the link, owing to the action of the spring 220. Upon starting the machine, therefore, the feed point is started into operation in timed relation to the other parts of the machine.

While it is preferred to employ the specific construction and arrangement of the parts shown and described, since this construction and arrangement is the simplest and most efficient embodiment of the invention which has yet been devised, it will be understood that this construction and arrangement is not essential except so far as specified in the claims, and may be varied or modified without departing from the broader features of the invention.

Having explained the nature and object of the invention, and specifically described one form of machine in which it may be embodied, what is claimed is:—

1. A chain stitch shoe sewing machine, having, in combination, a straight hook needle, mechanism for actuating the needle comprising a vibratory bar and a member connected with said bar for vibratory movement therewith, one of which is movable relative to the other to adjust the member longitudinally of the bar, connections between said member and the needle, means for independently vibrating the ends of said bar in directions transverse to its length, a work support, a presser foot, and means for relatively moving the bar and said member upon a change in the relative positions of the work support and presser foot due to a change in the thickness of the work to vary one of the limits of the needle stroke.

2. A chain stitch shoe sewing machine, having, in combination, a straight hook needle, mechanism for actuating the needle comprising a laterally vibratory bar and a member connected with said bar for vibratory movements with the bar and relatively movable longitudinally of the bar, means for supporting said bar for longitudinal movement to adjust the member longitudinally of the bar, connections between said member and the needle, means for laterally vibrating said bar to reciprocate the needle, a work support, a presser foot, and a connection for moving said bar longitudinally upon a change in the relative positions of the work support and presser foot due to a change in the thickness of the work to vary the position of said member longitudinally of the bar and thereby vary the needle stroke.

3. A chain stitch shoe sewing machine, having, in combination, a straight hook needle,

mechanism for actuating the needle comprising a laterally vibratory bar and a member connected with said bar for vibratory movement with the bar and relatively movable longitudinally of the bar, means for supporting said bar for longitudinal movement to adjust the member longitudinally of the bar, connections between said member and the needle, means for independently vibrating the ends of said bar in directions transverse to its length, a work support, a presser foot, and a connection for moving said bar longitudinally upon a change in the relative positions of the work support and presser foot due to a change in the thickness of the work to vary the position of said member longitudinally of the bar and thereby vary the needle stroke.

4. A chain stitch shoe sewing machine, having, in combination, a straight hook needle, mechanism for actuating the needle comprising a laterally vibratory bar and a member connected with said bar to vibrate therewith, one of which is movable relative to the other to vary the position of the member longitudinally of the bar, connections between said member and the needle, means for imparting independent lateral vibratory movements of different amplitudes to the ends of said bar, a work support, a presser foot, and mechanism for relatively moving said member and bar to adjust the member longitudinally of the bar upon a change in the relative positions of the work support and presser foot due to a change in the thickness of the work to vary the needle stroke.

5. A chain stitch shoe sewing machine, having, in combination, a straight hook needle, mechanism for actuating the needle comprising a laterally vibratory bar and a member connected with said bar for vibratory movement with the bar and relatively movable longitudinally of the bar, means for supporting said bar for longitudinal movement to adjust the member longitudinally of the bar, connections between said member and the needle, means for imparting independent lateral vibratory movements of different amplitudes to the ends of said bar, a work support, a presser foot, and a connection for moving said bar longitudinally upon a change in the relative positions of the work support and presser foot due to a change in the thickness of the work to vary the position of said member longitudinally of the bar and thereby vary the needle stroke.

6. A chain stitch shoe sewing machine, having, in combination, a straight hook needle, mechanism for actuating the needle comprising a laterally vibratory and longitudinally movable bar, a member connected with said bar for vibratory movement therewith and relatively movable longitudinally of the bar, swinging supports for said bar, means

for reciprocating said supports to vibrate the ends of said bar independently, a work support, a presser foot, and means for moving said bar longitudinally upon its swinging supports upon a change in the relative positions of the work support and presser foot caused by a change in the thickness of the work to vary the position of said member longitudinally of the bar and thereby 10 vary the needle stroke.

7. A chain stitch shoe sewing machine, having, in combination, a straight hook needle, mechanism for actuating the needle comprising a laterally vibratory and longitudinally movable bar, a block arranged to vibrate with said bar and relatively movable longitudinally of the bar, connection between the block and the needle, swinging supports for said bar, means for laterally 20 vibrating the bar to reciprocate the needle, a work support, a presser foot, and means acting upon a change in the relative positions of the work support and presser foot caused by a change in the thickness of the 25 work for swinging the bar lengthwise to vary the position of the block longitudinally of the bar and thereby vary the needle stroke.

8. A chain stitch shoe sewing machine, 30 having, in combination, a straight hook needle, mechanism for actuating the needle comprising a laterally vibratory bar and a block connected with said bar for vibratory movement therewith, one of which is movable relative to the other to vary the position of the block longitudinally of the bar, a shaft, cranks on said shaft and connecting rods between said cranks and said bar, arranged to impart independent vibratory 40 movements to the ends of said bar in directions transverse to the length of the bar, a work support, a presser foot, and means for relatively moving the bar and block to adjust the block longitudinally of the bar 45 upon a change in the relative positions of the work support and presser foot due to a change in the thickness of the work to vary one of the limits of the needle stroke.

9. A chain stitch shoe sewing machine, 50 having, in combination, a straight hook needle, mechanism for actuating the needle comprising a laterally vibratory bar and a block connected with said bar for vibratory movement therewith, one of which is movable relatively to the other to vary the position of the block longitudinally of the bar, connections between said block and the needle, a shaft, cranks of different throws on said shaft arranged on the same side of the 55 axis of the shaft, connecting rods between said cranks and the vibratory bar arranged to impart independent vibratory movements to the ends of said bar in directions transverse to the length of the bar, a work support, a presser foot, and a connection for

relatively moving the bar and block to adjust the block longitudinally of the bar upon a change in the relative positions of the work support and presser foot due to a change in the thickness of the work to vary 70 one of the limits of the needle stroke.

10. A chain stitch shoe sewing machine, having, in combination, a straight hook needle, mechanism for actuating the needle comprising a laterally vibratory and longitudinally movable bar, a block connected with said bar for vibratory movement therewith and relatively movable longitudinally of the bar, connections between said block and the needle, a shaft, cranks on said shaft and connecting rods between said cranks and said bar arranged to impart independent vibratory movements to the ends of said bar in directions transverse to the length of the bar, a work support, a presser foot, and means for moving said bar longitudinally about its connections with the shaft to vary the position of the block longitudinally of the bar upon a change in the relative positions of the work support and presser foot 85 due to a change in the thickness of the work to vary one of the limits of the needle stroke.

11. A chain stitch shoe sewing machine, having, in combination, a straight hook needle, mechanism for actuating the needle comprising a laterally vibratory and longitudinally movable bar, a block connected with said bar for vibratory movement therewith and relatively movable longitudinally of the bar, connections between said block and the needle, a shaft, cranks of different throws on said shaft arranged on the same side of the axis of the shaft, connecting rods between said cranks and the bar arranged to impart independent vibratory movements to the ends of said bar in directions transverse to the length of the bar, a work support, a presser foot, and a connection acting upon a change in the relative positions of the work support and presser foot due to a change in the thickness of the work to swing the bar longitudinally about its connections with the shaft to vary the position of the block longitudinally of the bar and thereby vary one of the limits of the needle stroke.

12. A sewing machine, having, in combination, a needle, a work support, a presser foot, means for lifting the presser foot from the work during each cycle of operations, mechanism for actuating the needle comprising a variable connection for causing a variation in the upward stroke of the needle upon a variation in the position of the presser foot due to a change in the thickness of the work, and locking means for maintaining the parts 110 of the variable connection in unvaried relative positions while the presser foot is lifted.

13. A sewing machine, having, in combination, a needle, a work support, a presser foot, means for lifting the presser foot dur- 120 125

- ing each cycle of operations, means for actuating the needle comprising a variable connection, connecting mechanism between said variable connection and the presser foot for 5 relatively varying the position of the parts of said connection upon a change in the position of the presser foot due to a change in the thickness of the work to vary the upward stroke of the needle, locking means for 10 maintaining the parts of said connection in unvaried position while the presser foot is being lifted, and a spring in said connecting mechanism for permitting a relatively yielding movement of the parts thereof as the 15 presser foot is lifted.

14. A sewing machine, having, in combination, a needle, a work support, a presser

foot, means for relatively moving the work support and presser foot away from each other during each cycle of operations, mechanism for actuating the needle comprising a variable connection for causing a variation in one of the limits of the needle stroke upon a change in the relative positions of the work support and presser foot due to a change in the thickness of the work, and locking means for maintaining the parts of the variable connection in unvaried relative positions while the work support and presser foot are moved relatively away from each other.

WILLIAM C. MEYER.

Witnesses:

CHESTER E. ROGERS,
RUTH E. WARD.

It is hereby certified that in Letters Patent No. 1,177,581, granted March 28, 1916, upon the application of William C. Meyer, of Beverly, Massachusetts, for an improvement in "Shoe-Sewing Machines," errors appear in the printed specification requiring correction as follows: Page 7, line 11, for the word "as" read ~~is~~ same page, line 15, for the reference-numeral "128" read 129; page 11, line 16, for the words "any other" read *another*; and that the said Letters Patent should be read with these corrections therein that the same may conform to the record of the case in the Patent Office.

Signed and sealed this 13th day of June, A. D., 1916.

[SEAL.]

R. F. WHITEHEAD,

Acting Commissioner of Patents
